APPARATUS FOR OPERATING A WELL
CABLE

Edwin J. Basye, Altadena, Calif.

Application May 23, 1939, Serial No. 275,233

11 Claims. (Cl. 74—25)

My invention relates to an apparatus designed for operating a cable in a well for any of the uses for which such a cable is employed, and particularly for operating a pump rod of a pump, or a cable operated down in a well for any purpose where the cable is raised by power and released to drop by gravity.

One practical application of my invention is to take the place of the usual walking-beam used in pumping oil wells, and it has among its salient objects to provide an improved mechanism which will make it possible to conveniently regulate the length of stroke desired or required for the particular job; to provide a mechanism which is simple, practical and efficient, and which does away with a great deal of the usual mechanism above the ground, as where the old walking-beam is used.

Another object of my invention is to provide a mechanism of the character referred to in which an operating cable is wound around a drum a few turns with its opposite ends connected, one end with the pump rod or other working part, and the other end of which is connected with a weight which operates to keep the cable taut, much as does the man who holds on to the free end of a cable operating on the usual capstan.

Another object of my invention is to provide in such a mechanism, a simple and practical means for automatically releasing the cable drum at the end of the power stroke, whereby the pump rod or other working part is released to fall by gravity to the down position, with means for automatically setting the mechanism at the end of the down movement to immediately start the lift or up stroke of said cable.

Other objects and advantages of my invention will appear from the following more detailed description of the same, taken in connection with the accompanying two sheets of drawings, on which I have illustrated one practical embodiment thereof. In the drawings:

Figure 1 is a vertical sectional view through a pit, showing my invention in side elevation in connection therewith, for operating a pump rod;

Figure 2 is an enlarged vertical sectional view through the center of the cable drum mechanism, taken on line 2—2 of Fig. 1;

Figure 3 is a diagrammatic view showing the cables in their relationships to the pump rod and the weight apart from the drums;

Figure 4 is a vertical sectional view taken on line 4—4 of Fig. 2;

Figure 5 is a vertical sectional view taken on line 5—5 of Fig. 2;

Figures 6 and 7 are sectional views of the same parts shown in Figs. 4 and 5, respectively, in other positions; and

Figure 8 is a horizontal sectional view taken on line 8—8 of Fig. 1, showing the lever mountings under the mechanisms shown in Figs. 4 to 7 inclusive.

Referring now more in detail to the drawings, Fig. 1 in particular, my invention as here shown for illustrative purposes is shown in combination with a pit 10, suitably walled, as may be desired, with concrete blocks, 11, 11, at the surface, opposite ends, across which, at the surface, are mounted two rails, 12, 12, seen in section in Fig. 2, upon which carrier brackets are mounted to move, each carrier bracket including a head portion 13, having a bearing box 14, with arms 15, 15, and a downwardly depending supporting arm or web 16, across the lower ends of which is mounted a shaft 17, secured therein. The main drive or operating shaft 18 is mounted through the bearing boxes 14, 14, and has rotatably mounted thereon a cable drum 19, having the flanges 19', 19', between which the cables, designated 20, 21, are wound, as indicated in Fig. 3. One end of the cables 20 and 21 are shown attached to a cross member 22, to which a pump rod 23 is attached, and the other ends of said cables are attached to a cross member 24, to which a counterweight 25 is mounted, as clearly indicated in Figs. 1 and 3.

As a means for moving the carrier brackets and drum mechanism on the tracks or rails 12, 12, a rod 26, is attached thereto, as at 27, and is threaded at its other end and extended through a member 28, with an internally threaded crank member 29 thereon for exerting pull on said carrier arms 15, as indicated in Fig. 1. This for the purpose of moving the mechanism over to the right far enough when it is desired to remove pump rod or pipe from the well, as will be understood.

Keyed to the main shaft 18, within the drum 19, in a cross arm or member 30, shown as having its lower end, as seen in Fig. 2, and Figs. 4 and 6, bifurcated and having pivotally mounted thereon, on a pivot pin 31, the lower ends of two brake shoe members, 32, 33, as clearly shown in Figs. 4 and 6. The end of the brake shoe member 32 is also bifurcated with the end of the member 33 therebetween on the pivot pin 31.

The upper end of said cross arm or member 30, is also bifurcated and has mounted therein a pinion 34, on a shaft 35, having its bearings 35', 35" in the sides of said cross arm. Said shaft 35 is

55

extended and is provided on its outer end with a second pinion 36.

The upper end of the brake shoe member 32 is provided with a rack portion 32' and the brake shoe member 33 is provided at its upper end with an offset portion which terminates in a rack 33', and these rack portions 32' and 33' are in mesh with the pinion 34, on the shaft 35, as clearly seen in Figs. 4 and 5, in different positions.

10 Mounted on the main shaft 18, in the open side of the cable drum 19, as seen in Fig. 2, is a disc or narrow drum 37, having formed on its upper side, as seen in Figs. 2, 5 and 7, a rack segment 37', in mesh with the pinion 36, on the shaft 35, which extends through an opening or slot 38 in said disc or narrow drum 37.

Also mounted on said main shaft 18, outside of said disc or narrow drum 37, is another disc or narrow drum 39, having around its edge an inwardly extended flange portion 39' and having shown integral therewith an inwardly positioned rack segment 40, also in mesh with the underside of pinion 36, as shown in Figs. 5 and 7, which are sectional views taken on the line 5—5 of Fig. 2, just inside of the web or disc body 39.

On the shaft 18, between said disc or drum members 37 and 39, are two discs, as 41 and 42, with a pad 43 therebetween, said discs 41 and 42 being connected with the larger discs 37 and 39, respectively, by pins 44 and 45. Two coiled expansion springs, as 46 and 47, are placed between the outer discs 37 and 39, and the inner smaller discs 41 and 42, putting a yielding pressure toward the pad 43 therebetween, as seen in Fig. 2.

35 Mounted around the face of the disc or narrow drum 37 is a brake band 48, having attached to one end a coiled spring 49, the other end of which spring is attached to the end of a lever or arm 50, the other end of which brake band 48 is anchored to an offset portion 50' at the pivoted end of said lever 50, as seen in Figs. 5 and 7.

Mounted around the face of the outer disc member 39 is a second brake band 51, having attached to one end a coiled spring 52, the other end of which spring is attached to the end of a lever or arm 53, the other end of which brake band 51 is anchored to an offset portion 53' at the pivoted end of the lever or arm 53. Figs. 5 and 7 show the same mechanisms in released positions and in locked positions, as again herein referred to.

Also mounted on said shaft 17, at the lower end of the side bracket webs or arms 16, 16, and 55 secured thereto by a set screw 54 is a rocker arm or lever 55, the opposite ends of which are positioned to be engaged by and moved, respectively, by the cross members 22 and 24, as said cross members are alternately raised and lowered, as 60 will be clear from Fig. 1, which operates to rock the shaft 17, and to also rock the arms or levers 50 and 53 for locking or releasing the brake bands on the drum elements 37 and 39, which in turn operate the pinions 34 and 36, for setting and 65 releasing the brake shoe members 32—33.

The use and operation of my invention as here shown for explanatory purposes may be briefly described as follows:

Assuming that the pump rod is down, as indicated in Figs. 1 and 4, and that the counterweight 25 is up and has engaged and moved rocker lever 55 to the position shown in Fig. 4. This operates to turn shaft 17 therewith, moving arm 50 down and arm 53 up, as seen in Fig. 5.

75 Arm 50 tightens brake band 48 on drum 37,

holding said drum 37 and its rack segment 37'. As shaft 35 is moving with the cross arm 30, and pinion 36 thereon is in mesh with said rack segment 37' being held (rack 40 on drum 39 being free), said shaft 35 is rotated, and in turn rotates pinion 34, operating between racks 32' and 33', which pinion 34 operates to expand brake shoes 32 and 33, in the cable drum 19, and thus drives said cable drum 19 with the cross arm 30, secured on the drive shaft 18, to wind up said cable and 10 pull said pump rod to the up stroke, where it engages said rocker lever 55, and moves it to the position shown in Fig. 6. This turns the shaft 17 correspondingly, raising arm 50 and lowering arm 53, thereby releasing brake band 48, on drum 37, and tightening brake band 51, on drum 39. The holding of drum 39, also holds its rack segment 40, which causes the pinion 36 to turn thereon, as it is moved by the arm 30, and shaft 35, on said rack segment 40. This turns pinion 34 in the opposite direction which operates through racks 32' and 33' to release the brake shoes 32 and 33, as seen in Fig. 6, permitting the cable drum to turn freely and thus allow the cable and pump rod to drop by gravity to the down position. The number of turns of the cable drum determines the length of the stroke and this makes it possible to get any length of stroke desired. The speed of the drive shaft 18, and the operating arm or member 30 therein, may be 20 regulated according to the production required. It will be noted that the cable and pump rod, or any other member attached to said cable, is pulled to the up position and then is allowed to drop freely as far as desired, or as far as the 25 counterweight will permit according to its position of attachment, and there is no forcing the rod down and no buckling thereof, as when the pump rod is attached to the usual walking-beam and the speed is much greater than can be had with a walking beam.

Thus I have provided a practical, efficient and economical cable operating mechanism, wherein a cable drum has thereon an operating cable to be connected with a work load, such as a pump rod, drill or any other load which is to be raised and dropped by gravity, with means for automatically controlling the operation thereof to positively drive said cable drum to raise said work load and to release said drum to permit the work load to drop, and in connection with which mechanism it is possible to regulate the length of stroke and to provide for a length of stroke impossible with a walking beam, now commonly used in so many oil wells.

And while I have shown and described in detail one practical embodiment of my invention, I am aware that many changes in the details of construction and arrangement can be made without departing from the spirit and heart of my invention, and I do not, therefore, limit my invention to the showing made, except as I may be limited by the hereto appended claims.

I claim:

1. A cable operating mechanism including a drive shaft, a cable drum mounted thereon, a cable around said drum with its opposite ends extended downwardly therefrom to be alternately raised and lowered as said drum turns in opposite directions, one end of said cable being adapted to be connected with a work load and the other end thereof connected with a counterweight, a driving element secured to said drive shaft to turn therewith, releasable means connected with said driving element for operatively 70 connecting and disconnecting said cable with said driving element.

connecting it with said drum for positively driving said drum in one direction to lift said work load, and means alternately operable by said cable ends for automatically releasing said driving element from said drum, whereby said drum can turn freely to permit said work load to drop, and for automatically again locking said driving element with said drum to again lift said work load.

10. 2. A cable operating mechanism including a drive shaft, a cable drum mounted thereon, a cable around said drum with its opposite ends extended downwardly therefrom to be alternately raised and lowered as said drum turns in opposite directions, one end of said cable being adapted to be connected with a work load and the other end thereof connected with a counterweight, a driving element secured to said drive shaft within said drum to turn with said shaft, releasable means connected with said driving element for intermittently connecting it with the interior of said drum for driving said drum in one direction, to lift said work load, and means operable to automatically release said driving element from said drum to permit said drum to turn freely and for again locking said driving element with said drum to lift said work load, and means on the opposite ends of said cable for automatically actuating said releasing means to alternately set and release said means for driving and releasing said cable drum.

3. A cable operating mechanism including a drive shaft, a cable drum rotatably mounted on said drive shaft, a cable around said drum with its opposite ends extended downwardly therefrom to be alternately raised and lowered as said drum is turned in opposite directions, one end of said cable being attached to a work load and the other end thereof connected with a counterweight, a driving element secured to said drive shaft within said cable drum, brake shoes connected with said driving element and adapted to be expanded and contracted to interlock said driving element with said cable drum and to release said drum, means for expanding and contracting said brake shoes, said means being controlled by said cable ends, and means on said cable ends to alternately actuate the means for expanding and contracting said brake shoes, whereby to drive said cable drum to lift the work load and to release it to let said work load drop.

4. A cable operating mechanism including a drive shaft, a cable drum rotatably mounted on said drive shaft, a cable around said drum and having its end connected with a work load, a counterweight having cable connections with said drum in opposition to the pull of said work load, a driving element secured to said shaft within said drum, means carried by said driving element adapted to be interlocked with said cable drum, mechanism adapted to be actuated to alternately interlock and release said driving element, to drive said drum or to release it to turn freely, and means connected with said cable on the work load end to actuate said mechanism in one direction to release said driving element from said drum, and means carried on the counterweight cable to actuate said mechanism in the opposite direction to interlock said driving element with said cable drum to raise said work load.

5. In a cable operating mechanism, a drive shaft to be power driven, a cable drum thereon having its end connected with a work load, a counterweight having cable connection around

said drum to oppose said work load pull on said drum, a driving element connected with said drive shaft to turn therewith within said drum, brake shoes connected with said driving element within said drum, rack and gear means carried by said driving element for expanding and contracting said brake shoes to interlock said driving element with said cable drum and for releasing said drum to turn freely on said shaft, and means operable to actuate said rack and gear means to expand and contract said brake shoes, and actuating elements connected with the work load cable and with the counterweight cable to alternately operate the means operable to actuate said rack and gear means, whereby to alternately expand and contract said brake shoes within said cable drum.

6. In a cable operating mechanism, a drive shaft to be power driven, a cable drum rotatably mounted thereon, a cable around said drum and having its end connected with a work load, a driving element secured to said drive shaft within said drum, means carried by said driving element for interlocking said driving element with the drum to drive said drum with said drive shaft, said means being releasable, and means connected with said cable and positioned with relation to the work load to actuate said releasable means on the up stroke of said work load, whereby to release said cable drum to turn freely and let said work load drop.

7. In a cable operating mechanism, in combination, a drive shaft, a cable drum rotatably mounted thereon, a cable around said drum and connected with a work load to be lifted and dropped, a driving element secured to said shaft within said drum, brake shoes carried by said element and expandable and contractible to interlock with said drum and to release said drum, rack and gear means for expanding and contracting said brake shoes, actuating means for rack and gear means, and means on said cable for engaging and actuating said actuating means.

8. A cable operating mechanism including in combination: a shaft to be power driven, a cable drum rotatably mounted on said shaft, a cable around said drum and having its end attached to a work load, a drive element secured to said shaft within said drum, a pair of brake shoes carried by said drive element within said drum, rack and gear means carried by said drive element for expanding and contracting said brake shoes to interlock said drum to said drive element and said shaft, a second drum mounted to rotate on said shaft and having rack and gear means therein connected with said first rack and gear means in said cable drum, a brake band operable on said second drum to hold it, whereby to cause the actuation of said first rack and gear means to expand said brake shoes in said cable drum, and means for tightening said brake band on said second drum, said last mentioned means being operable by said cable as it reaches its limit movement, whereby said drum is operated to pull said cable and said work load to the up position.

9. In a cable operating mechanism; a drive shaft, a cable drum rotatably mounted thereon, a cable around said drum to be operated up and down as said drum turns in opposite directions, a drive element secured to said drive shaft within said drum, brake shoes carried by said drive element within said drum, rack and gear means on said drive element to expand and contract said brake shoes, to lock said drum to said drive

shaft, a second drum rotatable on said shaft and having means for actuating said rack and gear means in one direction when held, a third drum on said shaft and having means for actuating said rack and gear means in the other direction when held, brake bands on said second and third drums, lever means for alternately tightening and loosening said brake bands, respectively, and means connected with said cable to operate said lever means when said cable reaches the two limits of movement, respectively, to operate said cable drum positively and to release it to turn freely on said drive shaft.

10. In a cable operating mechanism: a drive shaft, a cable drum rotatably mounted thereon, a cable around said drum with its ends extended therefrom and connected, respectively, with a work load and a counterweight, to be alternately moved up and down as said cable drum turns in different directions, a drive element secured to said drive shaft in said drum, brake shoes carried by said drive element within said drum to be expanded and contracted, means carried by said drive element for expanding said brake shoes to interlock with said drum for driving it in one direction, a second drum rotatable on said shaft adjacent said cable drum, a third drum rotatable on said shaft adjacent said second drum, operating connections from said second and third drums for actuating the means for expanding and contracting said brake shoes

in said cable drum, respectively, when said second and third drums are held against movement, brake bands on said second and third drums for holding them against turning, and means on said cable for alternately actuating said brake bands as said cable reaches its different limits of movement up and down, whereby to cause the interlocking of said cable drum with said drive shaft and for releasing it to turn freely on said drive shaft.

11. In combination with a well, a support, a drive shaft thereon, a cable drum rotatably mounted on said drive shaft, a cable around said drum with its ends extended downwardly from said drum, one end of said cable being connected with a work load in said well, the other end of said cable being connected with a counterweight, a drive element secured to said shaft and having means connected therewith for interlocking it with said drum for positively driving said drum in one direction, said means being releasable to free said drum, said releasable means being actuated up and down for alternately interlocking and releasing said cable drum with said drive shaft, and means on said cable for engaging and alternately actuating said releasable means as said cable reaches the up and down limits of movement, whereby the driving and releasing of said cable drum is automatically controlled.

EDWIN J. BASYE.
